UNITED STATES PATENT OFFICE.

WILLIAM C. VANNEMAN, OF ANDERSON, INDIANA, ASSIGNOR OF ONE-HALF
TO JENNIE C. HICKEY, OF LEIPSIC, OHIO.

MILEAGE-TICKET AND CASE.

SPECIFICATION forming part of Letters Patent No. 651,151, dated June 5, 1900.

Application filed April 17, 1899. Serial No. 713,255. (No model.)

To all whom it may concern:

Be it known that I, WILLIAM C. VANNEMAN, residing at Anderson, in the county of Madison and State of Indiana, have invented certain new and useful Improvements in Mileage-Tickets and Cases, of which the following is a specification.

The object of my invention is to provide a combined mileage-coupon ticket and the case therefor, the ticket being so connected that it will readily pull out, but cannot be moved back into the case. The case also is so constructed that it cannot be opened after the ticket is once folded and secured therein. The ticket is so printed that the number of miles used or the number of miles of coupons unused can in no way be determined without breaking the seal or breaking the original package-case, so as to immediately and completely expose the fact that the case had been tampered with. There are very many obvious advantages in the employment of such a mileage-ticket in a case. As no person can tell the number of unused coupons in the case, it will not be salable by scalpers or travelers. Again, the party purchasing the mileage book or case may be required to leave his signature with the ticket agent and may be required to sign the tickets taken off by the conductor on the train, which are compared by the auditor with the original signature and if found to be signed by an unauthorized person the purchaser will forfeit the rebate, which is frequently paid to the purchasers after the mileage tickets or coupons have all been used. Thus this system is adapted to be used with the rebate or the absolute sale of the mileage-tickets, whichever system the railroads may desire to employ.

The features of my invention are more fully set forth in the description of the accompanying drawings, forming a part of this specification, in which—

Figure 1 is the preferred form of the ticket-case before it is closed. Fig. 2 represents the ticket inclosed in the case and the case sealed. Fig. 3 is a longitudinal vertical section of Fig. 2. Fig. 4 is a modified form of the case.

a represents the back of the ticket-case.

b represents the front side.

c represents the inner cover, which is initially folded down upon the ticket.

d represents a flap provided with a tongue *e*, engaging in one or more slots *g* of the front cover.

h represents a locking-hook for holding the tongue in the slot.

Upon the inside of the back of the case is mounted a slat *i* of sufficient thickness to accommodate the folds of the ticket *T*, which is folded and laid into the space between the slat *i* and the lower end of the case *j*. Upon the outer cover *b* and upon the inside thereof is placed a slat *n*, which rests upon the protruding end of the ticket *T* when the cover *b* is folded down in place. The ticket is secured at one end within the case, the free end passing over slat *i* and under slat *n*, as shown in Fig. 3, and, issuing through the open end of the case, follows a tortuous frictional passage, rendering it impossible to insert the ticket-strip after it had been withdrawn. The slat *i* holds the folds of the ticket in place and yet allows the uppermost folds to be drawn out over slat *i* and under slat *n*, yet the ticket cannot be put back.

Instead of constructing the case so that it can be folded, locked, and sealed the covers of the case may be made without the lock and seal and the covers of the case firmly glued together, so as to prevent it from being opened without entirely destroying one of the walls of the case.

The coupons and the folds are preferably numbered in sets of tens or more; but no serial number for the entire number of coupons is employed. Say a ticket contained one thousand miles, these will be indicated by numerals serially arranged from "1" up to any given factor—say "10"—and of course there would be one hundred such series to make the total. Thus it is impossible for any person to determine without either the destruction of either the seal or the case the number of coupons used or unused.

The case will bear the ticket-number, as

50

55

60

65

70

75

80

85

90

95

shown in Fig. 4, which is also printed on the face of the ticket, preferably on each coupon; but the ticket-number may be placed on the inside face of the case, if desired, as shown in 5 Fig. 1.

The mouth of the case may be restricted in any convenient manner so as to allow the ticket to be pulled out in ribbon form; but I prefer slats or obstructions having square 10 shoulders, so as to hold the ticket folds in a secure manner.

Having described my invention, what I claim is—

1. A case for mileage-books closed at the 15 front and back, two sides and one end, friction devices attached to the opposing faces of the front and back near the open end and arranged one in front of the other to form a tortuous passage, and a mileage-strip secured 20 within the case, the free end passing between the friction devices and issuing from the open end of the case, substantially as specified.

2. A mileage-strip and ticket-case, the said case being closed upon the front, back, two 25 sides and one end, the strip secured at one end within the case, friction devices secured on opposite sides of the strip within the case near the open end, one being arranged in front of the other to form a tortuous pas- 30 sage, the said devices being adapted to engage between them the free end of the strip as it issues from the open end of the case, substantially as specified.

3. The combination of a mileage case and 35 ticket, the case being closed upon the front, back, two sides and one end, a mileage-strip secured at one end within the case, the said strip containing a given number of miles indicated by a repeating series of numerals 40 printed thereon running from "1" up to any selected factor of the sum total of miles, friction devices located between the covers near the open end arranged to form a tortuous pas-

sage adapted to frictionally engage the free end of the ticket substantially as described. 45

4. The combination of a mileage case and ticket the case being closed upon the front, back, two sides and one end, a mileage-strip secured at one end within the case indicated by a repeating series of numerals serially 50 printed thereon from one up to any selected factor of the sum total of miles, friction devices depending from the opposing face of front and back near the open end, one of said devices being arranged in front of the other 55 forming a tortuous passage adapted to frictionally engage the free end of the strip passing between them, substantially as described.

5. The combination with a permanently-closed case having an opening therein, of a 60 continuous ticket-slip in said case comprising a plurality of complementary parts or tickets each provided with indicating characters, the characters on the several parts or tickets being the same, and means for preventing the return of the ticket-slip to the case, substantially as specified. 65

6. The combination with a permanently-closed case having an opening therein, of a 70 continuous ticket-slip in said case comprising a plurality of complementary portions each provided with indicating characters, the characters on one portion having no relation to the characters on another portion whereby it is impossible to tell from one portion how 75 much of the slip remains in the case, and means for preventing the return to the case of a portion of the slip withdrawn, substantially as specified.

In testimony whereof I have hereunto set 80 my hand.

WILLIAM C. VANNEMAN.
